ABRAHAM PRESS, OF WILKINSBURG, PENNSYLVANIA, ASSIGNOR TO WESTINGHOUSE ELECTRIC & MANUFACTURING COMPANY, A CORPORATION OF PENNSYLVANIA.

RECEIVING SYSTEM.

Application filed June 17, 1920. Serial No. 389,538.

This invention relates to wireless triodes and more especially to those in which a grid is maintained more positive with respect to both a co-operating filament and a plate. One of the more important objects of my invention is to increase the detector sensitivity of such a device.

I have discovered that, by substantially balancing the accelerating potential of the filament-grid circuit by a retarding potential, the detector's sensitivity is materially increased for an incoming signal. This increased sensitivity, as a feature of my invention, is obtained by destroying the balance established between the accelerating and retarding potentials above described by introducing the voltage set up by the incoming signal into either one of the two opposing circuits. Thus, I have found, in particular, although a grid current is continually maintained between the filament and the grid, yet, for a given potential between the grid and plate, no current will flow through the telephones intercalated in the latter circuit, except for such values of the grid-filament potential as counterbalance the potential between the grid and the plate. As a further feature of my invention, therefore, I provide such an arrangement of circuits whereby the values of the plate current only exist for a given grid-to-plate difference of potential, after a predetermined value of the grid-filament potential has been reached.

In the prior art, it will be found that, for ordinary variations of the grid potential, a current, whether less or more, is always found to exist in the plate circuit. The above indicated property of a sudden springing into being of the plate current is especially valuable, since the detector sensitivity of the triode depends upon the curvature of the plate-current grid-voltage characteristic.

Other objects and features of the invention will naturally follow from an inspection of the drawings, when taken in conjunction with the accompanying descrip-

tion. Such features will also be made a part of the claims.

Figure 1 is a diagram representing one embodiment of my invention.

Figure 2 is a diagram representing an alternative form, wherein the incoming signal is impressed upon the grid-plate circuit.

Figure 3 is a diagram conformable to the showing of Fig. 1 except for the introduction of potentiometer devices for producing the voltage controls.

Figure 4 is a chart illustrating the relationship of the plate current to the variable grid potential or various plate-grid voltages.

A vacuum tube 1, of the usual type, is provided with three electrodes, viz: the filament 2, the grid 3 and the plate 4, to form a triode. Preferably, the grid is of the usual fine-mesh variety. It is usual to excite the filament by means of an adjustable battery arrangement 5 in order to provide a stream of current-carrying particles from the filament to the grid. An adjustable battery 6 is provided between the grid and the filament in such manner that the grid constitutes the positive pole of the above battery unit. Similarly, a second adjustable battery 7 is connected between the grid and the plate in such manner that the plate 4 constitutes the negative pole of such adjustable battery 7. In one form of my device, as in Fig. 1, I intercalate a telephone 8, or other equivalent indicating device, in the connections leading from the plate 4 to the battery 7. Thus, under the above circumstances, I include also a coupling coil 9 between the filament 2 and the battery unit 6. The coupling coil 9 may be of any desired type but I have shown it associated with an antenna 10 by means of an antenna-coupling-coil member 11.

In Fig. 2, the relative positions of the telephone 8 and the coupling coils 9 and 11 are shown as interchanged.

In Fig. 3, the arrangement, for the most part, is similar to that in Fig. 1, but, in order to provide more delicate adjustment

of the voltages between the filament-to-grid and grid-to-plate, potentiometers 12 and 13 are indicated having adjustable connections 14 and 15 for obtaining the required delicacy of adjustment. Preferably, I provide a variable-condenser connection 16 between the adjustable connections 14 and 15. The showing of Fig. 3, including as it does a condenser 16 together with a series coupling-coil member 9, has manifest advantages in those cases where tuning or resonance reinforcements are contemplated. The condenser 17 is similarly connected across the terminals of the telephone 8.

15 In Fig. 4, I have plotted the plate current of a triode against the accelerating potential of the battery 6 in the grid-filament circuit, while maintaining a constant retarding potential of the battery 7 in the grid-plate circuit. A number of curves are drawn, for various values of the retarding potential, as indicated, in order to determine the relative potential adjustments necessary to obtain the steepest slope of the plate-current accelerating-potential characteristic at the points of substantially zero current.

In the operation of my invention, I contemplate balancing the filament-to-grid voltage against the grid-to-plate voltage. 30 Ideally, under these circumstances, no current would then flow between the filament and the plate. On the other hand, current will undoubtedly flow between the filament and the grid. I have found, however, that 35 there is a critical grid-to-plate-voltage adjustment, see, for example, the 11-volt curve of Fig. 4, which gives the steepest rise in plate current for a given increment in the grid-to-filament voltage. Such type of adjustment, as a feature of my invention, thus 40 becomes an important matter, especially from the standpoint of a detector arrangement.

While I have described and illustrated 45 several embodiments of my invention, it will be apparent to those skilled in the art that various changes, modifications, substitutions, additions and omissions may be made in the apparatus without departing from 50 the spirit and scope of the invention.

I claim as my invention:

1. A method of receiving signals with a 55 triode valve having an intermediate grid electrode positive with respect to a plate and a cathode, comprising the steps of so balancing the opposing potentials of the grid-plate and grid-filament circuits that substantially zero plate-current is obtained and then subjecting such balanced triode to the influence of the signals.

2. The combination with a triode valve 60 having a cathode, an anode and an intermediately disposed grid, of means for giving the grid a positive potential with respect 65 to the cathode, and means for producing

a substantially balancing potential between the grid and anode.

3. In combination with a tube having a filament, a fine-mesh grid, and a plate; means for passing an electron current between filament and grid, and potential-producing means for neutralizing the electron current flow between grid and plate. 70

4. In combination with a vacuum-tube device having a pair of electrodes, means for causing an electron flow between said electrodes, a third electrode adjacent one of said electrodes of said pair, and further means for substantially balancing out an electron flow between said third electrode and said 80 adjacent electrode.

5. In combination with a vacuum-tube device having a pair of electrodes, means for establishing an electron flow between said electrodes, a third electrode adjacent one of said electrodes of said pair, further means for substantially balancing out an electron flow between said third electrode and said adjacent electrode, and additional means for disturbing said balance. 85

6. A detector comprising the filament, grid and plate of a triode valve, means connecting said filament and grid for passing a current toward said grid, further means connecting said grid and plate for substantially 95 balancing out any current flowing into said plate, and wave-influencing means and an indicating means in the connections between said filament and plate.

7. The combination with an electron tube 100 having a cathode, an anode and an intermediately disposed grid, of means for giving the grid a positive potential with respect to the cathode, further means for producing a substantially balancing potential between 105 the grid and anode, and still further means for disturbing said balance.

8. In combination with an electron tube having a filament, a plate and an intermediately disposed grid, means for giving the 110 grid a positive potential with respect to the filament, further means for producing a substantially balancing potential between the grid and plate, still further means for disturbing said balance, and additional 115 means for indicating said disturbance of the balance.

9. The combination with a triode valve having a filament, a grid and a plate, of means for producing a normally constant 120 grid-filament voltage, a source of signal current for temporarily increasing said grid-filament voltage, and means for causing the plate current to be existent only after a predetermined increased value of the grid-filament voltage has been reached. 125

10. In a method of operating an electron tube having substantially normally constant accelerating and retarding grid-filament and grid-plate potentials respectively, the steps 130

of varying one of said potentials in accordance with a signal and so adjusting the normally constant potentials as to obtain a maximum ascent characteristic of the plate current with respect to said varied potential.

11. In combination with a triode valve, a plurality of circuit means for making the intermediate electrode positive with respect to the remaining two electrodes of said triode, and a capacity coupling for said plurality of circuit means.

12. In combination with a triode valve, a plurality of circuit means for making the intermediate electrode positive with respect to the remaining two electrodes of said triode, and further means for providing a resonance coupling for said plurality of circuit means.

13. The combination with an electron tube having a filament, a grid and a plate, of a grid-plate circuit including a source of electromotive force, a grid-filament circuit including a source of electromotive force substantially opposing said first-mentioned electromotive force, said grid being more positive than the filament and plate, and a coupling between the two circuits.

14. The combination with an electron tube having a filament, a grid and a plate, of a grid-plate circuit including a source of electromotive force, a grid-filament circuit including a source of electromotive force substantially opposing said first-mentioned electromotive force, said grid being more positive than the said filament and plate, a coupling between the two circuits, an antenna and ground electrically associated with said coupling and a detecting device in one of said circuits.

15. The combination with an electron tube having a cathode, a grid and a plate, of a grid-plate circuit, a grid-cathode circuit, means for rendering said grid positive with respect to both plate and cathode, a source of signal impulses individual to one of said circuits and a translating device individual to the other of said circuits.

16. The combination with an electron tube having a cathode, a grid and a plate, of a grid-plate circuit, a grid-cathode circuit, means for rendering said grid positive with respect to both plate and cathode, a source of signal impulses individual to said grid-cathode circuit, and a translating device individual to said grid-plate circuit.

17. The combination with an electron tube having a cathode, a grid and a plate, of a grid-plate circuit, a grid-cathode circuit, means for rendering said grid positive with respect to both plate and cathode, a source of signal impulses individual to one of said circuits, a translating device individual to the other of said circuits, and a feed-back coupling device between the two circuits.

18. The combination with an electron tube having a cathode, a grid and a plate, of a grid-plate circuit, a grid-cathode circuit, means for rendering said grid positive with respect to both plate and cathode, a source of signal impulses individual to said grid-cathode circuit, a translating device individual to said grid-plate circuit, and a feed-back coupling device between the two circuits.

19. The combination with an electron tube having a cathode, a grid and a plate, of a grid-plate circuit, a grid-cathode circuit, means for rendering said grid positive with respect to both plate and cathode, and a coupling device between the two circuits.

20. The combination with an electron tube having a cathode, a grid and a plate, of a grid-plate circuit, a grid-cathode circuit, means for rendering said grid positive with respect to both plate and cathode, a source of signal impulses individual to one of said circuits, and means for so adjusting the relative potentials that the current in said grid-plate circuit during non-signalling periods may be reduced to a negligibly small value.

21. The combination with an electron tube having a cathode, a grid and a plate, of a grid-plate circuit, a grid-cathode circuit, means for rendering said grid positive with respect to both plate and cathode, a source of signal impulses in said grid-cathode circuit, and means for so adjusting the relative potentials that the current in said grid-plate circuit during non-signalling periods may be reduced to a negligibly small value.

22. The combination with an electron tube having a cathode, a grid and a plate, of a grid-plate circuit, a grid-cathode circuit, means for rendering said grid positive with respect to both plate and cathode, at least one of said circuits containing a translating device for signal currents, and means for so adjusting the relative potentials that the current in said grid-plate circuit during non-signalling periods may be reduced to a negligibly small value.

23. The combination with an electron tube having a cathode, a grid and a plate, of a grid-plate circuit, a grid-cathode circuit, means for rendering said grid positive with respect to both plate and cathode, a source of signal impulses individual to one of said circuits, a coupling device between the two circuits, and means for so adjusting the relative potentials that the current in said grid-plate circuit during non-signalling periods may be reduced to a negligibly small value.

24. The combination with an electron tube having a cathode, a grid and a plate, of a grid-plate circuit, a grid-cathode circuit, means for rendering said grid positive with respect to both plate and cathode, a source of signal impulses in said grid-cathode cir-

- cuit, a coupling device between the two circuits, and means for so adjusting the relative potentials that the current in said grid-plate circuit during non-signalling periods may be reduced to a negligibly small value.
25. The combination with an electron tube having a cathode, a grid and a plate, of a grid-plate circuit, a grid-cathode circuit, means for rendering said grid positive with respect to both plate and cathode, at least one of said circuits containing a translating device for signal currents, a coupling device between the two circuits, and means for so adjusting the relative potentials that the current in said grid-plate circuit during non-signalling periods may be reduced to a negligibly small value.
- 10 26. The combination with an electron tube having a cathode, a grid and a plate, of a grid-plate circuit and a grid-cathode circuit forming also a plate-cathode circuit, means for rendering said grid positive with respect to both plate and cathode, a source of signal impulses included in said plate-cathode circuit, and means for utilizing signal currents also included in said plate-cathode circuit.
- 15 27. The combination with an electron tube having a cathode, a grid and a plate, of a grid-plate circuit and a grid-cathode circuit forming also a plate-cathode circuit, means for rendering said grid positive with respect to both plate and cathode, a source of signal impulses included in said plate-cathode circuit, means for utilizing signal currents also included in said plate-cathode circuit, and feed-back coupling means between said grid-plate and grid-cathode circuits.
- 20 28. The combination with an electron tube having a cathode, a grid and a plate, of a grid-plate circuit and a grid-cathode circuit forming also a plate-cathode circuit, means for rendering said grid positive with respect to both plate and cathode, a source of signal impulses included in said plate-cathode circuit, means for utilizing signal currents also included in said plate-cathode circuit, and means for so adjusting the relative potentials that the current in said grid-plate circuit during non-signalling periods may be reduced to a negligibly small value.
- 25 29. The combination with an electron tube having a cathode, a grid and a plate, of a grid-plate circuit and a grid-cathode circuit forming also a plate-cathode circuit, means for rendering said grid positive with respect to both plate and cathode, a source of signal impulses included in said plate-cathode circuit, means for utilizing signal currents also included in said plate-cathode circuit, feed-back coupling means between said grid-plate and grid-cathode circuits, and means for so adjusting the relative potentials that the current in said grid-plate circuit during

non-signalling periods may be reduced to a negligibly small value.

30. In a method of operating an electron tube having substantially normally constant accelerating and retarding grid-filament and grid-plate potentials, the steps of varying one of said potentials in accordance with a signal and so adjusting the normally constant potentials as to obtain substantially no plate current during non-signalling periods and to obtain a maximum ascent characteristic of the plate current with respect to said varied potential.

70 31. In a method of operating a signaling system including an electron tube having a cathode, an anode and an intermediately disposed grid, together with grid-cathode and grid-anode circuits including sources of accelerating and retarding potentials, respectively, the steps of causing said potentials to be so adjusted, at times, that substantially no plate current is obtained, and causing said adjustment to be disturbed in accordance with a signal.

75 32. In a method of operating a signaling system including an electron tube having a cathode, an anode and an intermediately disposed grid, together with coupled grid-cathode and grid-anode circuits including sources of accelerating and retarding potentials, respectively, the steps of causing said potentials to be so adjusted, at times, that substantially no plate current is obtained, causing the potential in one of said circuits to be altered in accordance with a signal, and utilizing the resultant current variations in the other circuit.

80 33. In a signaling system, the combination with an electron tube having a cathode, an anode and an intermediately disposed grid, of grid-cathode and grid-anode circuits including sources of accelerating and retarding potentials, respectively, and means for causing one of said potentials to be varied in accordance with a signal.

85 34. In a signaling system, the combination with an electron tube having a cathode, an anode and an intermediately disposed grid, of coupled grid-cathode and grid-anode circuits including sources of accelerating and retarding potentials, respectively, means for causing the potential in one of said circuits to be altered in accordance with a signal, and means for utilizing the resultant current variations in the other circuit.

90 35. In a signaling system, the combination with an electron tube having a cathode, an anode and an intermediately disposed grid, of means including sources of accelerating and retarding potentials for causing substantially zero anode-current to be obtained, at times, and means for causing one of said potentials to be varied in accordance with a signal.

95 36. In a signaling system, the combination
